HAIR-TRIMMING COMB

William H. Ream, Johnstown, Pa., assignor of
one-half to Sarah Ream, Johnstown, Pa.

Application May 20, 1949, Serial No. 94,490

3 Claims. (Cl. 30—30)

1

My invention relates to hair-trimming combs of the type wherein means are provided to mount a razor blade on a front surface of the comb back for sliding movement into selected overlapping positions relative to the comb teeth so as to trim the hair by a combing operation.

With the foregoing in view, it is an object of my invention to provide an improved hair-trimming comb of the class described.

A further object is to provide an improved hair-trimming comb of the class described which includes means for releasably and frictionally locking the razor blade in a selected adjustable position relative to the comb teeth.

A further object is to provide an improved hair-trimming comb of the class described which includes an auxiliary comb having comb teeth, means mounting the auxiliary comb on the first-mentioned comb with the teeth of the auxiliary comb extending oppositely to the teeth of the first-mentioned comb, and means mounting the razor blade for adjustable overlapping movement relative to the teeth of the auxiliary comb, and/or to the teeth of the first-mentioned comb.

Other objects and advantages reside in the particular structure of the device, the structure of the several elements forming the same, combinations and sub-combinations of such elements, all of which will be readily apparent to those skilled in the art upon reference to the attached drawing in connection with the following specification, wherein the invention is shown, described and claimed.

In the drawing:

Figure 1 is a front elevation of the comb according to the invention;

Figure 2 is a horizontal sectional view taken substantially on the plane of the line 2—2 of Figure 1;

Figure 3 is a vertical sectional view taken substantially on the plane of the line 3—3 of Figure 1;

Figure 4 is a fragmentary front elevation of the comb with the movable parts removed therefrom;

Figure 5 is a transverse vertical sectional view showing a slight modification and taken substantially on the plane of the line 5—5 of Figure 6;

Figure 6 is a plan view showing a modification;

Figure 7 is an inverted front elevational view of the modification of Figures 5 and 6, showing parts removed and parts broken away;

Figure 8 is a perspective view of a part usable

2

with the form of Figures 1 to 4, inclusive, apart from the rest of the structure;

Figure 9 is a rear view of a razor-blade-carrier apart from the rest of the structure;

Figure 10 is a perspective view of the carrier of Figure 9;

Figure 11 is a bottom plan view of a locking device for the carrier apart from the rest of the structure.

10 Referring specifically to the drawing, wherein like reference characters have been used throughout the several views to designate like parts, 12 designates generally a pocket comb including a comb back 13 and a plurality of comb teeth 14 depending from the lower edge of the back. The front surface of the comb back 13 is formed with a rectangular recess 15 opening upwardly through the upper edge of the comb back. The upper edge of the comb back is recessed, as at 16, to provide an upper edge portion defining the upper limits of the recess 15 centrally of the side walls thereof for a purpose to be apparent hereinafter.

As best seen in Figures 1, 2, 3 and 8, a plate 18 of rectangular form is adapted to be seated in the recess 15 in laterally-inwardly-spaced relation to the side walls of such recess. The plate 18 is formed with a pair of laterally-spaced sockets 19 adapted to seat on the studs 17 extending forwardly from the floor of the recess 15, whereby to readily detachably mount the plate 18 in the recess. As best seen in Figures 2 and 3, the front surface of the plate 18 extends forwardly of the front surface of the comb back 13 and the front surfaces of the comb teeth 14 a short distance.

As best seen in Figures 9 and 10, a carrier 20 is provided for mounting a razor blade 21 on the front surface of the plate 18. The blade 21 is of the type having a pair of end tangs 22 extending laterally beyond the opposite ends of the upper and lower blade edges 23 and 24. The carrier 20 is generally rectangular in form and slightly longer than the width of the plate 18. Likewise, the carrier 20 is provided with upper and lower rearwardly-directed lugs 25 and 26, respectively, at each end of the carrier. Such lugs 25 and 26 are adapted to slidably engage the opposite end edges of the plate 18, whereby to slidably mount the carrier on the plate with the blade 21 sandwiched therebetween. Also, it will be noted that the end tangs 22 of the blade 21 are interposed between the upper and lower pairs of lugs 25 and 26, whereby the blade is readily detachably connected to the carrier for

50 sliding movement therewith on the plate 18. As

55

aforesaid, the forward surface of the plate 18 extends forwardly of the front surface of the comb back 13, whereby the lower lugs 26 clear the front surface of the comb back to permit sliding of the carrier and its blade below the bottom wall 27 of the recess 15 so as to dispose the lower edge 24 of the blade in overlapping relation to the comb teeth 14, as clearly shown in Figure 3.

To maintain the blade 21 in a selected overlapped position relative to the comb teeth 14, means now to be described have been provided. Thus, the forward surface of the carrier 20 has a pin 28 fixed thereto and projecting forwardly therefrom. A button 29 is formed with a socket 30 on its rear face slidably receiving the pin 28 therein, whereby to mount the button for forward and rearward sliding movement relative to the front surface of the carrier 20. An expansive spring 31 is interposed between the button 29 and the front surface of the carrier 20, whereby to load the button for forward movement relative to the carrier. A cover plate 32 is fixed to the comb back 13 in any suitable manner, as by the screws or rivets 33. The cover plate 32 is disposed in overlying relation to the carrier 20. Also, the cover plate 32 is formed with a vertically-extending dovetail slot 34 into which the button 29 extends. Side edges 35 of the button 29 are complementary to the undercut walls of the slot 34 and frictionally engageable therewith under the load of the spring 31, whereby to frictionally lock the carrier 20 in vertically-adjusted positions in the slot 34. Thus, to adjust the carrier 20, it is necessary only to press inwardly on the button 29 to release the sides 35 thereof from the undercut side walls of the slot 34, whereby the carrier is freely vertically adjustable so as to vary the overlapping relation of the lower blade edge 24 with the comb teeth 14.

Referring now to Figures 5, 6 and 7, a rectangular auxiliary comb 40 is there shown as being substituted for the plate 18. The comb 40 is substantially the same width as the plate 18 and has its rear surface formed with rearwardly-directed sockets 41 receiving the studs 17 therein, whereby to readily detachably mount the auxiliary comb in the recess 15. As in the first-described form of the invention, the end edges 42 of the auxiliary comb 40 provide a slidable engagement with the lugs 25 and 26 to slidably mount the carrier 20 thereon. However, in this arrangement, the forward surface of the auxiliary comb 40 is substantially flush with the forward surface of the comb back 13, whereby the lowermost lugs 26 engage the bottom wall 27 of the recess 15 to limit downward sliding movement of the carrier in such recess. Also, it should be noted that the auxiliary comb 40 has upper and lower sets of teeth 43 and 44, respectively. As best seen in Figure 7, the lower teeth 44 are finer than the comb teeth 14, but are coarser than the upper teeth 43. Obviously, the auxiliary comb 40 may be reversed in the recess 15 to position the lower teeth 44 uppermost if desired. Likewise, as best seen in Figure 5, the carrier 20 is readily adjustable upwardly to vary the overlapping relation of the upper blade edge 23 relative to the upper comb teeth 43. Obviously, if desired, the thickness of the auxiliary comb 40 could be increased to equal that of the plate 18, whereby the carrier 20 would be downwardly-slidable into the same overlapping position relative to the comb teeth 14, as in the first-described form of the invention. Moreover, 75

while I have shown and described what is now thought to be the preferred forms of my invention, it is to be understood that the same is susceptible of other forms and expressions. Consequently, I do not limit myself to the precise embodiments shown and described hereinabove except as hereinafter claimed.

I claim:

1. A hair-trimming comb comprising an elongated substantially flat comb back, a plurality of teeth along one edge thereof, said comb back being provided with a recess in one face extending inwardly from the other edge thereof and terminating at a point spaced from said one edge, there being a rectangular cut-out extending inwardly from said other edge of said comb back intermediate the walls of said recess, spaced studs positioned within said recess and projecting from the floor of said recess intermediate the bounding edges thereof, an auxiliary comb adapted to be reversibly positioned within said recess and detachably mounted on said studs, said auxiliary comb having teeth along opposed edges thereof, the teeth on one edge of said auxiliary comb being of a different size than the teeth on the other edge, with the teeth on one edge overlying said cut-out, a razor blade carrier positioned in face to face abutting relation with respect to said auxiliary comb and having means adapted to support a razor blade in confronting relation to said auxiliary comb, and mounted in said recess for reciprocating movement, a longitudinally extending cover plate superimposed upon said carrier and fixedly secured to said comb back, said cover plate being provided with a dovetail slot extending inwardly from one of its longitudinal edges intermediate the ends thereof, and hand actuatable means extending through said slot and operatively connected to said carrier for effecting the reciprocatory movement of the latter.

2. A hair-trimming comb comprising an elongated substantially flat comb back, a plurality of teeth along one edge thereof, said comb back being provided with a recess in one face extending inwardly from the other edge thereof and terminating at a point spaced from said one edge, there being a rectangular cut-out extending inwardly from said other edge of said comb back and intermediate the walls of said recess, spaced studs positioned within said recess and projecting from the floor of said recess intermediate the bounding edges thereof, an auxiliary comb adapted to be reversibly positioned within said recess, there being spaced sockets on said auxiliary comb slidably receiving said studs, said auxiliary comb having teeth along opposed edges thereof, the teeth on one edge of said auxiliary comb being of a different size than the teeth on the other edge, with the teeth on one edge overlying said cut-out, a razor blade carrier positioned in face to face abutting relation with respect to said auxiliary comb and having means adapted to support a razor blade in confronting relation to said auxiliary comb and mounted in said recess for reciprocating movement, a longitudinally extending cover plate superimposed upon said carrier and fixedly secured to said comb back, said cover plate being provided with a dovetail slot extending inwardly from one of its longitudinal edges intermediate the ends thereof, a pin carried by said carrier and projecting through said slot, and hand actuatable means extending through said slot and operatively con-

nected to said carrier for effecting the reciprocatory movement of the latter.

3. A hair trimming comb comprising an elongated substantially flat comb back, a plurality of teeth along one edge thereof, said comb back being provided with a recess in one face extending inwardly from the other edge thereof and terminating at a point spaced from said one edge, there being a rectangular cut out extending inwardly from said other edge of said comb back and intermediate the walls of said recess, spaced studs positioned within said recess and projecting from the floor of said recess intermediate the bounding edges thereof, an auxiliary comb adapted to be reversibly positioned within said recess and detachably mounted on said studs, said auxiliary comb having teeth along opposed edges thereof, the teeth on one edge of said auxiliary comb being of a different size than the teeth on the other edge, with the teeth on one edge overlying said cutout, a razor blade carrier positioned in face to face abutting relation with respect to said auxiliary comb and having opposed pairs of lugs on the confronting face for receiving therebetween a razor blade in confronting relation to said auxiliary comb, and mounted

in said recess for reciprocating movement, a longitudinally extending cover plate superimposed upon said carrier and fixedly secured to said comb back, said cover plate being provided with a dovetail slot extending inwardly from one of its longitudinal edges intermediate the ends thereof, and hand actuatable means extending through said slot and operatively connected to said carrier for effecting the reciprocatory movement of the latter.
